UNITED STATES PATENT OFFICE

FREDERICK A. ANTON, OF TOPEKA, KANSAS

ASSEMBLY SUPPORT FOR LATERAL ARM AWNINGS

Application filed May 26, 1930. Serial No. 455,729.

This invention relates to store front awnings, and more especially to that type embodying a plurality of lateral arms adapted to unfold in the unwinding and spread of the awning fabric and to refold as the awning fabric is rewound, and still more particularly to the means for effecting adjustment of the folding arms whereby a greater or lesser pitch or inclination for the fabric shall be obtained.

10 My object in this application is to provide simple easily operated means whereby adjustment of each foldable arm in a vertical plane, can be efficiently effected after its supporting hanger is secured to the front 15 wall of a store front or to the transom bar or the like, of such store front.

With this general object in view, the invention consists in certain novel and useful features of construction and organization as 20 hereinafter described and claimed; and in order that it may be fully understood, reference is to be had to the accompanying drawings, in which :

Figure 1 is a side elevation showing a hanger, a fragment of a foldable lateral arm and the elements for supporting said arm on the hanger and adjusting the arm in a vertical plane to vary the inclination or pitch of the awning fabric, not shown.

25 Figure 2 is a front view.

Figure 3 is an inner face view of the foldable arm-carrying bracket.

Figure 4 is an inner face view of the cap and the ring at the same side of the hanger head in the same relative position which they 35 occupy in Figure 1.

Figure 5 is a vertical section on the line V—V of Figure 1.

Figure 6 is an inverted plan view of the 40 head end of the hanger.

Figure 7 represents a fragmentary detail perspective view of the foldable arm-carrying bracket.

Figure 8 is a detail perspective view of one 45 of a pair of tapered rings of the device.

Figure 9 is a detail perspective view of the cap member of the device.

Figure 10 is a detail perspective view of the swivelled bolt.

Figure 11 is a detail perspective view of one 50

of a pair of collars, the figure disclosing the threaded collar.

Referring to the drawings in detail, 1 indicates a hanger adapted to be secured flatly and vertically against the front of a building or a transom bar thereon, not shown, in any conventional manner. In practice there will be two or more of these hangers for each awning, but as the construction of the hanger and its associated parts is identical in all cases, a description of one will be sufficient to fully disclose the invention. The hanger is substantially obtuse-angle-shaped in side view, and at its front end terminates in a tubular head 2 disposed horizontally and parallel with the back face of the hanger. The opposite ends of the head are provided with notches 3, preferably in a plane below and forward of the axis of the head, and at the base of said notches the head is formed with oppositely facing annular shoulders 4.

A pair of rings 5 fit in opposite ends of the head and against the said shoulders respectively, and said rings are provided with downwardly and forwardly inclined arms 6 provided with alined perforations 7, the arms fitting snugly in said notches respectively so as to be incapable of turning movement relative to the head. A centrally perforated cap member 8 fitting against one of said rings and/or the corresponding end of the head, is provided with a depending arm 9 disposed at a downwardly-diverging angle with respect to the arms of said rings, and said arm 9 is provided with a hole 10 at the same distance from the axis of the head as the holes of the arms of said rings. The cap member is also provided at its inner side with a conical extension 11 disposed concentrically of the central perforation of said member, but of larger diameter both internally and externally than said hole, and in the inner end of said flange 11 are diametrically opposite notches 12.

A bracket 13 fits against the opposite end of the head from the cap, and/or against the ring engaging said end, and is provided with a conical extension 14 having a central hole 15 axially alined with the hole of the arm of the cap member. Said extension 14, adjacent the bracket, fits snugly and rotatably in the

adjacent ring member, and inward of the latter is of reduced diameter so as to fit into the opposing end of the extension 11 of the cap member, and said extension 14 is provided at diametrically opposite sides with a pair of external ribs 16 engaging the notches 12 of the extension of the cap member, so that the latter and the bracket shall be interlocked together as regards rotatable movement.

10 A bolt 17 extends through the hanger head and alined holes of the bracket and the cap member, and at one end has an angular head engaging a correspondingly shaped socket 18 in the bracket, and a nut 19 engages said bolt

15 and the opposing face of the cap member so that the latter and the bracket may be clamped firmly against the opposing faces or ends of the head of the hanger or the corresponding faces of the said ring members, and the

20 bracket is provided in alinement with the hole in the arm of the cap member with a corresponding hole 19^a. The bracket has an upright pivot bolt 20 forming a support for the folding arm 21, only the inner member of

25 the folding arm being disclosed as it is of the conventional type shown in my Patent No. 1,118,463, of November 24, 1914. The outer member of the folding arm as indicated in said patent, is pivoted to the outer end of the

30 inner member, and ordinarily forms a support for the pole (not shown) to which the outer end of the awning fabric, not shown, is connected, the inner end of said fabric engaging a roller, not shown, upon which the fabric is wound to effect the folding of the arms and from which it is unwound to permit the arms to unfold and project outwardly from the building for the purpose of spreading the awning for service.

40 A collar 22 is fitted between the perforated ends of the arms of the rings and is provided at diametrically opposite sides with outwardly projecting trunnions 23 pivotally engaging the perforations of said arms respectively.

45 A bolt 24 extends pivotally through said collar and between the arms of the cap and bracket, and the head of said bolt bears against the outer or front face of said collar. A retaining device 25 engages the bolt and

50 bears against the inner face of said collar so that the latter shall, in effect, bear a swivelled relation to the bolt. A second collar 26 interposed between the perforated arm of the cap and the perforated portion of the bracket, is

55 threaded on said bolt 24, and said collar is provided with a pair of trunnions 27 respectively engaging pivotally with the alined holes in the arm of the cap and said bracket, the arrangement being such that when the

60 bolt is turned it shall effect forward or rearward travel as the case may be, of the collar, and thereby effect corresponding rotation of said cap and bracket. This rotation is for the purpose of disposing the bracket so that

65 the folding arm carried thereby shall, when

unfolded, project downwardly and forwardly at such an angle as to give the awning fabric, when stretched, the requisite pitch or inclination, and this result can be accomplished very quickly and efficiently by the mere turning of the bolt 24. After the adjustment required has been attained, the nut 19 can be screwed home so as to clamp the cap and bracket in rigid relation to the hanger head or to said rings, so that it shall be impossible for any one to change the adjustment by turning the bolt 24 without first loosening or unclamping the nut 19.

It will be apparent that a construction such as described is a very simple, strong, durable and efficient construction and conveniently accessible at all times, and while I have illustrated and described the preferred embodiment of the invention, it will be apparent that it is susceptible of modification in minor particulars without departing from the principle of construction and mode of operation involved or from the spirit and scope of the appended claims.

I claim:

1. In a store front awning, a hanger having a horizontal tubular head, a pair of rings fitting the respective ends of the head and provided with arms projecting beyond the periphery of the head, the rings being rigid with the head as regards rotatable movement, a cap and bracket fitted at opposite ends of the head at the outer sides of said rings and interlocked together as regards rotatable movement, means for holding the cap and bracket against separating movement, a collar carried by the arms of the rings and bearing a pivoted relation thereto, a second collar carried by the cap and bracket and bearing a pivoted relation thereto, and a bolt extending through said collars and bearing a swivelled relation to one of them and a threaded relation to the other.

2. In a store front awning, a hanger having a horizontal tubular head, a pair of rings fitting the respective ends of the head and provided with arms projecting beyond the periphery of the head, the rings being rigid with the head as regards rotatable movement, a cap and a bracket fitted at opposite ends of the head at the outer sides of said rings, and provided with extensions interlocked together within the head, as regards rotatable movement, a collar carried by the arms of the rings and bearing a pivoted relation thereto, a second collar carried by the cap and bracket and bearing a pivoted relation thereto, a bolt extending through the said collars and bearing a swivelled relation to one of them and a threaded relation to the other, a headed bolt extending through the cap, bracket, hanger head and rings, and adjustable means on said bolt for securing the cap and bracket in rigid relationship with the hanger head.

3. In a store front awning, a hanger having a horizontal tubular head provided with notches in the ends of the head, a pair of rings fitting in the respective ends of the head and having arms extending through said notches and preventing rotatable movement of the rings, a cap and a bracket fitted at opposite ends of the head at the outer sides of the rings and projecting beyond the periphery of the head, a collar pivotally mounted between and on the arms of the rings, a second collar between and pivotally mounted on the cap and bracket, and a bolt extending through said collars and bearing a swivelled relation to one of them and a threaded relation to the other. 70
4. In a store front awning, a hanger having a horizontal tubular head provided with notches in the ends of the head, a pair of rings fitting in the respective ends of the head and having arms extending through said notches and preventing rotatable movement of the rings, a cap and a bracket fitted at opposite ends of the head at the outer sides of the rings and projecting beyond the periphery of the head, a collar pivotally mounted between and on the arms of the rings, a second collar between and pivotally mounted on the cap and bracket, a bolt extending through said collars and bearing a swivelled relation to one of them and a threaded relation to the other; said cap and bracket having extensions interlocked together within the head, as regards rotatable movement, a headed bolt extending through the bracket, the hanger head, the said rings and said cap, and a retaining nut engaging the bolt for effecting approaching movement of the bracket and cap and for securing said parts in rigid relationship to the hanger. 80
5. In a store front awning, a hanger having a horizontal tubular head provided with notches in its ends, a pair of rings fitting in and against the head and provided with arms extending respectively through said notches, a bracket fitting at one end of the head and provided with a conical extension projecting through the adjacent ring, a cap fitting at the opposite end of the head and provided with a conical extension projecting through the adjacent ring and bearing an interlocked relation as regards rotatable movement, with the said conical extension of the bracket, and provided with an arm; said bracket and cap arm having oppositely-disposed holes, a collar fitting between the arms of the rings and provided with oppositely-projecting trunnions pivotally engaging the holes in the respective ring arms, a second collar between the arm of the cap and said bracket and provided with oppositely-projecting trunnions pivotally engaging the holes respectively of the cap and bracket, and a headed bolt extending through said collars and bearing a swivelled relation to one of them and a threaded relation to the other and adapted when turned in one direction or the other to effect approaching or receding movement of said collars and rotative movement of said bracket and cap with respect to the hanger. 90
